US0D1048909S

(12) **United States Design Patent** (10) **Patent No.:** **US D1,048,909 S**
(45) **Date of Patent:** **** Oct. 29, 2024**

(54) **CARBON MONOXIDE GAS ALARM**

(71) Applicant: **Shenzhen Cinyue Electronic Technology Co., Ltd.**, Shenzhen (CN)

(72) Inventor: **Pei Zhang**, Shenzhen (CN)

(**) Term: **15 Years**

(21) Appl. No.: **29/942,479**

(22) Filed: **May 15, 2024**

(30) **Foreign Application Priority Data**

Apr. 28, 2024 (CN) 202430246920.6

(51) **LOC (14) Cl.** **10-05**

(52) **U.S. Cl.** **D10/106.2**
USPC .....

(57) **CLAIM**

The ornamental design for a carbon monoxide gas alarm, as shown and described.

DESCRIPTION

FIG. 1 is a front elevation view of a carbon monoxide gas alarm showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and,

FIG. 8 is another perspective view thereof.

The broken lines depict portions of the carbon monoxide gas alarm that form no part of the claimed design.

1 Claim, 8 Drawing Sheets
